CAR SEAT

Robert W. Weeden, Scotch Plains, N.J., assignor to
Union Carbide Corporation, a corporation of New
York

Filed Oct. 29, 1963, Ser. No. 77,197

Term of patent 7 years

(Cl. D15—1)

FIG. 1

FIG. 2

FIG. 3

FIG. 4

FIG. 5

FIG. 1 is a front perspective view of a car seat embodying my design;

FIG. 2 is a bottom view on a reduced scale;

FIG. 3 is a top view of the seat of FIGURE 2;

FIG. 4 is a side elevational view; and

FIG. 5 is a rear elevational view thereof.

I claim:

The ornamental design for a car seat, as shown.
